Application filed March 17, 1891. Serial No. 385,428. Term of patent 7 years.

To all whom it may concern:

Be it known that I, STEELE F. ROBERTS, a resident of Allegheny city, in the county of Allegheny and State of Pennsylvania, have 5 invented a new and original Design for Handles for Spoons, Forks, Button-Hooks, &c.; and I do hereby declare the following to be a full, clear, and exact description thereof.

My design consists, essentially, in a handle 10 for spoons, forks, and like articles of silver-ware, having its top formed of a coat of arms composed of a shield and a castle above the same.

The accompanying drawing illustrates my 15 design by a face view of the upper end of the spoon, fork, or other article.

In said drawing, the top *a* illustrates my design, the coat of arms having a shield *b* and a castle *c* above the same.

The shank *d* illustrated has the design of 20 twisted wire; but the ornamentation of the shank forms no part of the design.

The design may be employed with spoons, forks, knives, buttoners, and like silver-ware for the table or toilet. 25

What I claim is--

The design for a handle for spoons, forks, and like silver-ware herein shown and described.

In testimony whereof I, the said STEELE F. 30 ROBERTS, have hereunto set my hand.
